UNITED STATES PATENT OFFICE.

NICHOLAS O. KENNIKER, OF CHICAGO, ILLINOIS, ASSIGNOR TO DURABLE BOX CO., OF CHICAGO, ILLINOIS, A CORPORATION OF ILLINOIS.

BOX AND THE LIKE.

1,325,493.

Specification of Letters Patent.

Patented Dec. 16, 1919.

Application filed April 21, 1916. Serial No. 92,613.

To all whom it may concern:

Be it known that I, NICHOLAS O. KENNIKER, a citizen of the United States of America, residing at Chicago, in the county 5 of Cook and State of Illinois, have invented certain new and useful Improvements in Boxes and the like, of which the following is a description.

My invention belongs to that general 10 class of boxes, crates, and the like, of the knock-down type, that is, of the type where the side walls, top and bottom may be constructed at a convenient point where lumber material is cheap, and may be shipped 15 out in the knock-down form to the point where they are to be used, at which point they may be readily assembled for use without skilled labor, and at a minimum of expense. My invention has among its objects 20 the production of cases of the kind described, and fittings therefor, that are simple, convenient, compact, durable, efficient and satisfactory, for use wherever found applicable. The invention has among its 25 further objects the production of efficient means for securing and locking the parts together at the corners or juncture of the sides and ends and bottom and top, as may be desired. Other objects and advantages of the 30 construction herein shown and described will be obvious to those skilled in the art from the disclosure herein made.

To this end my invention consists in the novel construction, arrangement and combination of parts herein shown and described, and more particularly pointed out in the claims.

In the drawings, wherein like reference characters indicate like or corresponding 40 parts,

Figure 1 is a perspective view of a box embodying my invention;

Fig. 2 is a central longitudinal section of the same substantially in line 2—2 of Fig. 3;

Fig. 3 is a central transverse section of the same;

Fig. 4 is a sectional view indicating the method of assembling the proximate side and end walls;

Fig. 5 is a similar section showing the parts illustrated in Fig. 4, brought together to form a corner;

Fig. 6 is a similar section showing the

construction at the fourth or last corner in assembling the walls of the box;

Fig. 7 is a similar section showing a modification, and

Fig. 8 is another modification of the same.

In boxes and crates of the kind described, in view of the increased cost of the rough material, as well as the decrease in bulk, for shipping, and storage purposes, it has become desirable from a point of economy and convenience, to construct the side and end walls, as well as the top and bottom of 60 boxes, cases and crates at the point where lumber is cheap. These may then be packed compactly in the knock-down form, requiring the minimum of space, and without any waste material at all, may be shipped to the 65 point where they are to be used.

In boxes of this character, it is desirable that convenient means may be provided to assemble the various parts to complete the finished box. This means should be so 75 formed as not to require skilled labor, nor special tools, and the completed article should possess sufficient strength and durability to satisfactorily perform the duties for which it is desired.

In the drawings, a well known form of case is illustrated, in which 1—1 are the end walls and 2—2 the side walls, 3 the top and 4 the bottom.

As clearly shown in Fig. 4, one or the 85 other or both of the proximate ends of the side or end walls 1 and 2 are notched as at 5, so that the two parts will come into notched engagement. Binding rods 6 are provided, each having each end bent at a 90 right angle, as at 7, and of a sufficient length to pass through the wall of the box and lie upon cleats 9, as shown, and it is again bent at an angle to provide the ends 8. These lock rods for at least three corners of the 95 box are substantially straight, as shown in the full and dotted lines at the bottom of Fig. 4. At suitable points, and preferably close to the edge of the cleats 9, apertures 10 afford openings through the side and end walls of sufficient size to permit the bent ends 8 of the rods to pass therethrough.

The proximate end and side walls 1 and 2, shown in Fig. 4, may be brought to substantially the position shown in full and 105 dotted lines in that figure, permitting the

ends 8 of the rod to be inserted in the apertures 10 and pass therethrough to a point where they will lie upon the inner surface of the box. The free ends of the end and 5 side walls may then be brought toward each other, first forming substantially an obtuse angle shown in Fig. 4, and later to complete the angle corner shown in Fig. 5. This brings the two parts in notched engagement 10 at the ends, as indicated, forcibly bending the rod about the corner, binding the two parts firmly together, the extreme ends of the rod engaging and locking upon the inner surface of the box, as shown. As shown 15 in Fig. 1, preferably three of such binding rods are employed at each corner of the box.

It is obvious that at least three corners of the box can be assembled in the manner indicated, but the parts of the fourth corner 20 cannot be brought into the position shown for assembling. The binding rods for the fourth corner, which I have marked 11 to distinguish them, are preferably substantially bent to form several completed rods 25 when assembled, as shown in Fig. 6. Thus it will be seen when the side and end walls 1-2 of the fourth corner are brought together to the position shown in Fig. 6, the end 12 of the rod 11 may first be threaded 30 through the side wall, and the other end 13 may be brought around the corner of the box, and is of sufficient flexibility to permit the end 13 to be forced through the notched opening 14 formed in the wall, key 18 not 35 being in place. Sufficient clearness is provided between the edge of the cleat 15 and the bend 17 of the rod to permit the parts to be so assembled. When this is done, 40 suitably connecting the end and side walls as a whole, a key 18 may then be forced into the position between the edge of the cleat 15 and the part 17, clearly shown in Fig. 1, forcing the part 17 outward to its limit, and firmly binding the parts together, thus 45 preventing accidental withdrawal of the end 13 from the wall of the box sufficiently to cause accidental disengagement of the parts.

Fig. 7 is a modification of the form shown in Fig. 6, in which a plate 19 is 50 placed within the box, with a screw 20 passing therethrough, as well as through the wall of the box, and firmly seated in the key 18. It is obvious that the key 18 could not be removed from its position except 55 from the interior of the box, and by first releasing the plate 19, preventing tampering with the box from the outside.

Fig. 8 shows a slightly different modification, in which a bolt 21 secures the key 18 60 in position, with a nut 22 located inside the box and preventing disengaging the bolt from its position by outside manipulation.

Thus far we have referred to the assembly 65 of the side and end walls of the box.

However, as clearly shown in Figs. 1, 2 and 3, the top 3 may be attached at its rear edge to the wall of the box in a similar manner, thus as clearly shown in Fig. 3, the engaging rods 23 may have one end attached to 70 the rear wall 2 of the box, as indicated at 24, while the other end engages the cover 3 of the box in the same manner, the rods being secured at a point which is shown in substantially the same manner, as heretofore 75 described. In referring to the assembling of the corners of the box, the edge of the cover may be secured in like manner to that described in Fig. 6, thus as shown at the upper left hand corner of Fig. 2 the rods 80 25 have one end passing through and engaged with the cover of the box at the rear of the cleat 26, and the lower end passing through the enlarged openings in the front wall 2, with keys 27 forced between the bend 85 of the rods 25, and the cleat 28. The keys may be secured in position by screws or other suitable means to prevent their accidental disengagement.

If preferred, the keys 27 may be positioned upon the top of the box rather than on the side operating in substantially the same manner, the enlarged openings in such a case being formed in the top of the box rather than the front wall. In forming the 90 box it is preferred that suitable cross grooves be made in the outer surface of the several cleats, in which the rods are sunk, thus embedding them in the cleats, and preventing the rods catching on any obstruction when 95 the boxes are moved along or are applied one upon another. The bottom 4 of the box may be constructed in any preferred manner, and secured in position to the walls of the box also in any preferred manner. 100 As clearly shown in Figs. 2 and 3, the bottom is preferably provided with a central longitudinal cleat 29, between which and the bottom 4 is positioned a longitudinal rod 30, having its ends 31 bent upward at a 105 right angle, and outwardly as at 32, to be seated apertures formed in the end parts or walls of the box for that purpose. The outer ends 32' may be provided and turned over or clenched on the outside of the case. 110 The bottom also preferably has cleats 33 at its edges, firmly secured to the bottom of the box, and recessed at the outer edges of the bottom, to receive the lateral shoulders 34 of the metal plate 35, which is firmly secured to the front and rear side walls of the box. The bottom is placed in position as the side walls are assembled, thus permitting the engagement of the parts as described. This engagement of the several 115 parts firmly secures the bottom in position, insuring great rigidity in the box, which has a great strength in the connection of the various parts.

The entire box as thus constructed is ex- 120 125 130

tremely rigid and very strong, and may be set up in a few moment's time by unskilled labor. It may be disassembled or knocked down as readily, for storage or shipping purposes, as before set forth.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:—

1. In a device of the kind described and in combination, side and end walls, a plurality of binding members for securing one of the corners of the adjacent walls together, each member consisting of an integral rod having one end extended through an aperture in one of the walls, and thence bent at an angle to prevent withdrawal of the rod therefrom, the other end of the rod thence extended tightly around the corner of the box, and through an aperture in one of the walls with the end engaging the proximate wall, and means on the exterior of one of the walls for locking said members in place and preventing the withdrawal thereof.

2. In a device of the kind described and in combination, side and end walls, a plurality of binding members for securing one of the corners of the adjacent walls together, each member consisting of a rod having one end extended through an aperture in one of the walls, and thence bent at an angle to prevent withdrawal of the rod therefrom, the other end of the rod thence extended tightly around the corner of the box, and through an aperture in one of the walls with the end engaging the proximate wall, the apertures in said last mentioned wall of a size to permit the insertion or withdrawal of the end of the binder when the corner of the box is brought together, and means at the exterior of said wall for preventing the withdrawal of said binding members.

3. A box comprising side and end walls with transverse cleats arranged near the ends thereof, and a bottom connected to and carried by said walls, in combination with means for connecting one of the corners of said side walls comprising a plurality of binding members, said binding members each comprising an integral piece of wire offset adjacent each of its ends at substantially a right angle, and of a length to project through the walls, and again offset adjacent the free ends, said side and end walls provided with apertures therethrough adjacent said cleats, said binding members as-

sembled at said corner with the ends passed through the apertures in the walls and lying upon the inner faces thereof, the intermediate sections of said members imbedded in the outer surface of the cleats, the cleat at the end of one wall provided with a key member, the apertures at said cleat of a size to extend under the cleat when the entire cleat is secured to the wall, whereby the ends of the binding members at the loose corner in assembling the box, may be projected through said enlarged apertures and the key member thereafter positioned to lock the binder in place.

4. In a box comprising abutting side and end walls, the combination of a plurality of binding members for one of said corners, each consisting of an integral piece of wire bent substantially intermediate the ends with a suitable offset adjacent each of said abutting box ends, said corner provided with apertures, the apertures on one end being enlarged and relatively equal to the length of the offset at the free end of the wire, and means on the exterior of said wall for partially covering said enlarged apertures, and locking said wires in place.

5. A box comprising side and end walls, a plurality of binding members for securing the corners of the adjacent walls together, each member consisting of an integral rod having one end extended through the aperture in one of the walls, and thence bent at an angle outwardly to prevent its withdrawal, the other end of the rod thence extended tightly around the corner of the box with the end having frictional engagement with the proximate wall in a like manner, the resilient action of the member tending to maintain the outward ends in contact with the box.

6. A box comprising side and end walls, a plurality of binding members for securing the corners of the adjacent walls together, each member consisting of a rod having one end extending through an aperture in one of the walls and thence bent at an angle outwardly to prevent the withdrawal of the rod therethrough, the other end of the rod thence extended tightly around the corner of the box with the end engaging the proximate wall in a like manner, the outwardly extending ends being unattached to the walls of the box, the resilient action of the rod serving to hold said ends in frictional engagement with the walls.

In testimony whereof, I have hereunto signed my name in the presence of two subscribing witnesses.

NICHOLAS O. KENNIKER.
